CLAIM

The ornamental design for door lever, as shown and described.

DESCRIPTION

FIG. 1 is a side perspective view of a door lever according to my new design.

FIG. 2 is a front view of the door lever as in FIG. 1.

FIG. 3 is a back view of the door lever as in FIGS. 1-2.

FIG. 4 is a top view of the door lever as in FIGS. 1-3.

FIG. 5 is a bottom view of the door lever as in FIGS. 1-4.

FIG. 6 is an end view of the door lever as in FIGS. 1-5; and, FIG. 7 is an opposite end view of the door lever as in FIGS. 1-6.

The broken lines shown in FIG. 3 are unclaimed subject matter and form no part of the claimed design. The broken lines which define the bounds of the claimed design form no part thereof.
